DESIGN FOR A BADGE OR SIMILAR ARTICLE

John Edward Slavin, New Haven, Conn.

Application January 20, 1939, Serial No. 82,497

Term of patent 3½ years

To all whom it may concern:

Be it known that I, John Edward Slavin, a citizen of the United States, residing at New Haven, county of New Haven, State of Connecticut, have invented a new, original, and ornamental Design for a Badge or Similar Article, of which the following is a specification; reference being had to the accompanying drawing, forming a part thereof.

The figure is a face view of a badge or similar article showing my new design.

The design has no substantial thickness.

I claim:

The ornamental design for a badge or similar article, as shown and described.

JOHN EDWARD SLAVIN.
